UNITED STATES PATENT OFFICE.

JOHN P. ODGERS, OF PHILADELPHIA, PENNSYLVANIA, ASSIGNOR TO THE
A. M. COLLINS MANUFACTURING COMPANY, OF SAME PLACE.

DESIGN FOR A CARD-MOUNT.

SPECIFICATION forming part of Design No. 23,933, dated January 1, 1895.

Application filed September 22, 1894. Serial No. 523,843. Term of patent 7 years.

To all whom it may concern:

Be it known that I, JOHN P. ODGERS, a citizen of the United States, residing in Philadelphia, Pennsylvania, have invented a new and original Design for a Card-Mount, of which the following is a specification.

My design is fully shown in the accompanying drawing.

My design relates to a pattern or border for a card mount and is shown upon an oblong, rectangular card. Obviously, however, the outline of the card forms no part of the design, the essential or characteristic feature of which consists of a narrow band having, longitudinally disposed thereon, a continuous vine-like figure, the entire surface of the band

outside the said figure being roughened or stippled.

a, represents the card; *f*, the roughened or stippled surface of the narrow band, while *g*, represents the vine-like figure.

I claim—

The design for a card mount border, substantially as described and shown.

In testimony whereof I have signed my name to this specification in the presence of two subscribing witnesses.

JOHN P. ODGERS.

Witnesses:

HENRY HOWSON,
JOSEPH H. KLEIN.
